ing in an embodiment shown by way of example. FIG. 1 is a vertical sectional view showing a crucible with a skull at its mouth. FIG. 2 shows a preparatory position before the forcing-off. FIG. 3 shows the position for forcing-off the skull with the aid of the apparatus according to the invention.

In FIG. 1, 1 designates a typical form of a skull at the mouth of a crucible 2.

According to FIG. 2, an oxygen lance 3 mounted on the stand 4 is used to make half-ring cuts 5 on opposite sides when the crucible is in a tilted-down position e.g. at an angle of 18°. In this way, a ring 6 is cut out at the narrowest part of the vessel to separate the outer cone 1' from the inner cone 1".

In FIG. 3, the forcing-off nose 7 is carried by the hinged flap 8. The latter is hinged by a pin 9 to the main beam 10 of the platform structure. The flap 8 is adjustable by means of the hydraulic cylinder 11, which is suitably fed by a small rotary pump unit 12. In the position shown in dotted lines, the flap is disposed outside the arcuate path of the skull. In the position shown in solid lines, the flap is in operative position on the arcuate path. The forcing-off surface 13 of the forcing-off nose is so inclined that the force tending to force off the skull 25 has always a component which acts on the flap and tends to restore the flap to its original position, when the friction between the skull and the forcing-off nose is taken into account. The support afforded by the hydraulic cylinder opposes this component. In this arrangement, the force tending to force off the skull can be limited by setting a pressure limiting valve. When the force tending to force off the skull exceeds an allowable limit, which is determined by the drive, the valve will respond and the forcing-off flap will yield to the increased force.

It is essential in the entire structure that the pump unit must be designed only for adjusting the forcing-off flap. This requires only a small pressure and consequently a small power. The force tending to force off the skull is applied through the crucible drive. To prevent damage 40 to the crucible drive, the pressure limiting valve is mounted separately from the pump installation.

What I claim is:

1. An apparatus for forcing off skulls from the mouths of tiltable steelmaking converters, comprising a tiltable converter, a support, a flap hingedly connected to said support, a forcing-off nose on said flap movable into a path described by a skull on said converter mouth during the tilting of said converter, a hydraulic pressure cylinder connected to said flap and said support for forcing said nose against said skull, means for supplying hydraulic pressure to said cylinder and means for limiting the pressure supplied to said cylinder to a predetermined skull-severing pressure.

2. An apparatus as set forth in claim 1 wherein the forcing-off surface of said nose is inclined at an angle such that the reaction force produced on said nose by a skull during forcing off of the skull is directed to oppose the forcing action of said pressure cylinder.

ABSTRACT OF THE DISCLOSURE

This invention relates to apparatus for removing skulls from the mouths of crucibles or converters and includes a pivoted member having an inclined nose portion which is forced against the skull during tilting of the converter or crucible by a hydraulic pressure system including a pressure-regulating device for limiting the maximum force with which the skull-removing nose is pressed against the skull to avoid damaging the converter during removal of the skull.

This invention relates to an apparatus for forcing off skulls from the mouths of tiltable crucibles or converters.

During the operation of refining vessels, a mixture of slopped slag and steel particles in the form of a sintered mass, described as a skull, accumulates at the mouth of the vessel and must be removed from time to time. This removal involves undesired standstill times.

Various methods may be adopted to remove a skull: The skull may be burnt off with oxygen flames or may be blown off with impact and thrusting devices when the crucible is in a tilted position. In many cases, the mouth of the crucible and the skull adhering thereto were moved by means of the tilting drive against a rigid obstacle and the skull was forced off by the force of the crucible drive. This method, however, gives rise to unforeseeable forces, which react on the drive and may easily damage or even destroy the same. For this reason, all crucible manufacturers prohibit the use of the tilting drive to force off skulls. It has been found in practice, however, that the skull is still forced off by the tilting drive because this is the quickest, simplest and most convenient method.

It is an object of the invention to provide an apparatus which permits of forcing off the skull by means of the tilting drive without risk of adverse effects on the crucible drive.

The apparatus according to the invention promises a yielding forcing-off nose associated with adjustable pressure limiting means which is arranged to be movable in an arcuate path described by the skull during the tilting of the crucible.

The forcing-off nose is desirably mounted on a hinged flap, which is hydraulically operated, and the hydraulic system comprises a pressure limiting valve corresponding to the predetermined maximum of the force tending to force off the skull.

The forcing-off surface of the forcing-off nose should have such an inclination that a restoring component of force acting on the forcing-off nose and directed toward the pressure limiting means is obtained in the operative position while the skull is being forced off.

The apparatus according to the invention has the advantage of permitting with a very slight structural expenditure the use of the tilting drive for forcing off skulls, which practice is otherwise dangerous with regard to the guarantee.

The invention is illustrated in the accompanying draw-
